Dec 53

Ozra Ripley & N. S. Vedder of Troy N. Y.

assignors to

Samuel M. Blure of Rochester N. Y.

Letter Patent No 531. Dated Dec 7. 1852

The schedule referred to in these Letter Patent and making part of the same

To all whom it may concern,

Be it known that we Ozra Ripley and N. S.

Vedder of Troy in the County of Rensselaer and State of New York have invented or produced a new and original design of back stove, which we call the "Peach Branch Airtight" and we do hereby declare that the following is a full, clear, and exact description of the same reference being had to the annexed perspective drawing, making a part of this specification.

The ornamental design of our stove consists in the arrangement of Peach branches (a) on the panels of the front doors (AA) oven doors (BB) and fire doors (C) and in the combination of the ornamental moulding (b) with the plain

Res. 53

moulding (c) forming the frames of the doors, also in the combination of the ornamental moulding (d) and plain moulding (e) forming a border to the jamb (D) and front plates (E) and (F) & the mouldings (f) forming the border of the top plate (G) and hearth (H). The leg (I) is ornamented with a peach branch (h).

Having thus described our design of cook stove what we claim as new and due to secure by Letters Patent is the ornamental design and configuration of cook stove such as herein described and represented in the annexed drawing
